DESIGN.

C. L. DREHER.

HANDLE FOR CANES, UMBRELLAS, &c.

19,853.

Patented May 27, 1890.

UNITED STATES PATENT OFFICE.

CHARLES L. DREHER, OF LANCASTER, PENNSYLVANIA.

DESIGN FOR A HANDLE FOR CANES, UMBRELLAS, &c.

SPECIFICATION forming part of Design No. 19,853, dated May 27, 1890.

Application filed April 19, 1890. Serial No. 348,748. Term of patent 3½ years.

To all whom it may concern:

Be it known that I, CHARLES L. DREHER, of Lancaster, in the county of Lancaster and State of Pennsylvania, have invented certain new and useful Improvements in Designs for Cane and Umbrella and Parasol Handles; and I do hereby declare the following to be a full, clear, and exact description of the invention, such as will enable others skilled in the art to which it pertains to make and use it, reference being had to the accompanying drawings, which form part of this specification.

My invention relates to an improvement in designs for cane, umbrella, and parasol handles; and it consists in a handle having its upper end formed into a crook or hook which is closed at its lower end, and which is provided with ornamental work upon its sides, so as to give it an ornamental appearance, as will be more fully described hereinafter.

The accompanying photographic illustration represents a side elevation of a handle which embodies my invention.

A represents the handle, which has its outer end formed into a hook or crook which is bent upon an even or regular curve to the point B,

and from this point to the end the handle is bent or curved in an opposite direction and made to approach the side of the handle, so as to close the crook at this point. This curved end has grooves or cuts which form a raised ornamental work upon its sides, and the extreme end terminates in a volute C. The regular curved part of the handle has a number of grooves or corrugations formed in the sides of the handle, and along these grooves are formed little beads or points D. Extending up the side of the handle from near its lower end is a plant G, having laterally-extending branches which have flowers at their ends, and this plant or flower rises from the scrolls of ornamental work H.

Having thus described my invention, I claim—

The design for a cane, umbrella, or parasol handle, substantially as herein shown and described.

In testimony whereof I affix my signature in presence of two witnesses.

CHAS. L. DREHER.

Witnesses:

J. L. LYTE,
A. ROSENSTEIN.
